UNITED STATES PATENT OFFICE.

GEORGE ALMON MINZEY, OF BROCKTON, MASSACHUSETTS, ASSIGNOR TO ELLERY C. WRIGHT, OF BROCKTON, MASSACHUSETTS.

HINGED LAST.

1,120,324.

Specification of Letters Patent.

Patented Dec. 8, 1914.

Application filed February 12, 1913. Serial No. 747,945.

To all whom it may concern:

Be it known that I, GEORGE ALMON MINZEY, a citizen of the United States, and resident of Brockton, county of Plymouth, State of Massachusetts, have invented an Improvement in Hinged Lasts, of which the following description, in connection with the accompanying drawings, is a specification, like letters on the drawings representing like parts.

In the manufacture of shoes by the aid of hinged lasts, it is very essential that the last shall be exceedingly strong at the joint, in order to endure the leveling pressures and other strains brought upon the last, especially when it is bottom side up. This problem has proved so difficult that it has been the aim of a great many inventors ever since the advent of the hinged last.

My invention aims to solve this problem in connection with the type of last consisting of a forepart and heel part transversely severed by lines of cut forming an upper V-shaped gap to permit the heel part to swing upwardly on the forepart.

I aim to secure the great strength desired by avoiding cutting away the wood of the last as much as possible, and by providing a rod like hinge mounted in connection with the heel thimble and "E. C. W. bolt," so as to give a 3-branch support and resistance in the solid wood of the heel part, my preferred construction also including a rectangular transverse ledge or corner of the forepart seated within a reentrant angle or corner of the heel part (when the last is extended) for resisting twisting strains in connection with said 3-branch construction in the heel.

In the drawings, Figure 1 shows a preferred form of my last in side elevation, partly broken away for clearness of illustration; Fig. 2 is a horizontal sectional view, taken in line with the connecting rod axis; and Fig. 3 is a view similar to Fig. 1 of another embodiment of my invention.

The forepart 1 and heel part 2 have their adjacent ends 3, 4, cut along lines to provide a rectangular bearing at 5, with abutting portions 6 extending from that point downward. Connecting these two parts is a cylindrical member 7, preferably in the form of a solid rod fitting snugly into a hole bored lengthwise into the heel part, and mounted at the forepart on a steel pintle pin

8 to turn when the heel part is swung upwardly, the hole in the forepart being formed as indicated at 9 to permit of this swinging movement. The rear end of the rod member 7 is secured by an E. C. W. bolt 10 (having the construction and advantages set forth in U. S. Patents Nos. 605,768, June 14, 1898, and 642,945, February 6, 1900). Directly under the heel thimble 11, which is forced down under great pressure from the dotted position 12, so as to put all three members 11, 10, and 7, under more or less compression strain with relation to the wood of the heel part. The forepart and heel part will preferably be held extended by any suitable means, as, for example, by a spring 13.

In the construction shown in Fig. 3 the internal construction is very nearly the same as already described, excepting that the line of cut which severs the forepart from the heel part is slightly different so as to form a knuckle 14 at the rear end of the forepart seated within a socket 15 at the front end of the heel part, and the pintle 8 is raised higher in the forepart than it is in Figs. 1 and 2, in order to bring the two points 8 and 10 more radically out of line with the grain of the wood than in the other construction, and also so as to have the pivotal point in the forepart eccentric to the knuckle. Otherwise the construction in both forms of my invention is the same.

In operation it will be seen that not only is the heel portion of the last cut away to a minimum degree, inasmuch as the wood is integral or uncut entirely around the rod member 7, which has no play or movement therein whatever, but the union has a 3-branch resistance in the heel member in connection with the thimble. The result is that the last has very great strength to resist "breaking" strains, such as those produced by the leveling machine, for example. The steel pin 8 is preferably tapered so as to tighten the parts together when inserted.

In both forms of my invention the last opens freely, inasmuch as the contacting ends of the forepart and heel part immediately move out of engagement with each other as soon as the heel part is flexed upwardly. The great advantage, however, of the last resides in the strong heel construction and the 3-branch support which the hinged member or rod 7 has beneath the

thimble 11; Even if the rod should tend to wear loose in its tight recess, this tendency would be prevented by the unyielding engagement therewith of the thimble 11. 5 This thimble is always bearing upon the jack spindle of the machine on which the last is supported whenever any "breaking" strains are being applied to the bottom of the last, and accordingly the resistance of 10 the jack and of the jack spindle is thus transmitted through the thimble to the 3-branch anchorage against which the thimble presses.

Having described my invention, what I claim as new and desire to secure by Letters Patent is:

A hinged last, having a forepart and a heel part, a thimble in said heel part, and a

three-branch supporting means for said thimble, consisting of a cylindrical member 20 connecting the forepart and heel part, having one end portion pivotally fitted in the forepart, and the other end portion rigidly fitted in the heel part and extending under the thimble, and a tension bolt under the 25 thimble passing through the heel part and said cylindrical member, whereby said thimble is supported by the tension bolt and the cylindrical connecting member.

In testimony whereof, I have signed my 30 name to this specification, in the presence of two subscribing witnesses.

GEORGE ALMON MINZEY.
